UNITED STATES PATENT OFFICE

159,813

AUTOMOBILE WIND DEFLECTOR OR SIMILAR ARTICLE

Harold Karton, Burbank, Calif.

Application August 13, 1949, Serial No. 4,496

Term of patent 7 years

(Cl. D14—6)

To all whom it may concern:

Be it known that I, Harold Karton, a citizen of the United States, residing at Burbank, in the county of Los Angeles, State of California, have invented a new, original, and ornamental Design for an Automobile Wind Deflector or Similar Article, of which the following is a specification, reference being had to the accompanying drawing, forming a part thereof.

Figure 1 is a perspective view of an automobile wind deflector or similar article embodying my new design.

Figure 2 is an edge view thereof.

Figure 3 is a top view thereof.

I claim:

The ornamental design for an automobile wind deflector or similar article, as shown.
HAROLD KARTON.
